UNITED STATES PATENT OFFICE.

BERT A. LITTLE, OF OKEMAH, OKLAHOMA.

DRAWER-SLIDE.

1,071,006.

Specification of Letters Patent. Patented Aug. 19, 1913.

Application filed March 12, 1912. Serial No. 683,316.

To all whom it may concern:

Be it known that I, BERT A. LITTLE, citizen of the United States, residing at Okemah, in the county of Okfuskee and State 5 of Oklahoma, have invented certain new and useful Improvements in Drawer-Slides, of which the following is a specification.

This invention relates to improvements in drawer slides and has for its object the provision of a drawer slide by which the drawer will be supported firmly in a horizontal position when withdrawn far enough to permit inspection of its contents and by which the accidental release of the drawer from its 15 support will be prevented.

A further object of the invention is to provide a drawer slide of such a construction that when the removal of the drawer is necessary for any purpose it may be easily 20 and quickly released and removed from its support.

The invention seeks further to simplify and improve the construction of drawer slides to the end that the efficiency and durability thereof will be increased without increasing the cost of production.

The preferred embodiment of my invention is illustrated in the accompanying drawings, which are to be taken as part 30 hereof, and the invention will be hereinafter first fully described and then particularly pointed out in the appended claim.

In the drawings: Figure 1 is a perspective view of a drawer partly withdrawn 35 from a desk and showing my improved slide applied thereto. Fig. 2 is an enlarged view of the slide in its projected adjustment. Fig. 3 is a similar view looking at the opposite side of the slide. Fig. 4 is an elevation 40 showing the slide in its retracted position. Fig. 5 is an end view.

The desk 1 and the drawer 2 may be of the usual or any preferred construction and are shown for illustrative purposes only, it being understood that my improved slide may 45 be fitted to the drawers of any article of furniture, such as bureaus, sideboards, etc.

To the inner face of the side of the desk or to a partition therein, I secure a base 50 member 3 having its upper and lower edges formed into ribs or cleats 4 constituting guides or runways for the intermediate member 5 of the slide. The upper guide 4 is reduced in width at its rear portion 55 whereby to provide a shoulder or stop 6 at or about its center which is engaged by a

projection or tooth 7 at the upper rear corner of the intermediate member 5 to limit the movement of the said intermediate member and thereby prevent the same being entirely withdrawn from the base member. 60

The base member 3 is preferably constructed of a metal plate, having its edges doubled upon itself and secured to the article of furniture by suitable fastenings inserted 65

through openings 8, as will be readily understood. The intermediate member 5 is likewise preferably constructed of a metal plate having its edges doubled on itself to form reinforcing ribs which will fit within the guides 4 so as to prevent the member 5 of the slide playing so loosely upon the base member as to permit dislodgment of the drawer, but at the same time fit in said guides in a sufficiently loose manner to 70

freely slide therein. The doubled-over or under-turned edges 9 of the intermediate member also constitute guides or runways for the edges of the front or drawer-attaching member 10, which is also preferably constructed of a metal plate, secured to the side of the drawer by screws or similar fastenings 11 inserted through openings 75

provided therefor near the ends of the member. The edges of the member 10, however, 80 are not doubled upon themselves but are offset so as to provide the ribs 12 adapted to engage the guides 9 and thereby maintain the drawer in a horizontal position while at the same time permitting its free movement. The lower guide 9 on the intermediate member 5 is constructed with a shoulder or stop 13 in its upper edge and at a point determined by the size of the drawer. A 85

hook or gravity catch 14 is pivoted on the outer side of the member 10 and is adapted to engage the said stop 13 when the drawer is opened to its full extent so that the accidental removal of the drawer from the desk or other article of furniture will be prevented. 90

At the same time, if the removal of the drawer is necessary for any reason, the hook or catch 14 may be manually disengaged from the said stop 13 by merely inserting the end of the finger through an 100 opening 15 provided for that purpose in the intermediate member 5 and then lifting the hook from its engagement with said stop, as will be readily understood.

As the drawer is pulled out the drawer- 110 attaching member 10 of the slide will be first drawn forward through its engagement

with the intermediate member 5 until the catch 14 engages the stop 13, after which the intermediate member of the slide will be drawn forward until the projection 7 5 engages the stop or shoulder 6, in which position further outward movement of the drawer will be prevented. As the drawer is returned to its closed position the members of the slide will telescope backwardly until 10 they assume the relative positions shown in Fig. 4, which, it will be noted, is very compact so that they lie entirely within the lines of the article of furniture and will not detract from its appearance.

15 The slide devised by me may be applied to any drawer now in use without necessitating any reconstruction or re-modeling of the same and will be found highly efficient, as it will positively prevent the accidental 20 removal of the drawer and the consequent dumping of its contents and will also hold the drawer level while its contents are being inspected. Inasmuch as the slides cannot warp, the drawer will move freely at all 25 times and binding of the same in its support cannot occur. The several parts of the slide may be easily stamped up out of sheet metal and consequently the slide may be produced at a very slight cost. It is to 30 be understood, of course, that the base member 3 and the drawer attaching member 10 need not be as extensive as the forms shown, as the intermediate portions of these members may be omitted, it being essential only 35 that the guide-ways or ribs of said members be employed, and the gravity catch or hook may be pivoted directly upon the side of the

drawer. I, therefore, wish it to be understood that changes may be made in the details of construction without departing from 40 the spirit or scope of my invention as the same is defined in the following claim.

Having thus described my invention, what I claim as new is:

A drawer slide comprising a base member 45 having its edges formed into guides, the upper guide having a vertical shoulder at an intermediate point of its length, an intermediate member having the guides formed on its upper and lower edges and engaging 50 the guides on the base member, a projection at the rear end of said intermediate member on the upper edge thereof adapted to engage the shoulder on the base member, a stop on the lower edge of the intermediate member, 55 said member being provided with an opening adjacent said stop, a drawer attaching member slidably fitted in the guides on the intermediate member, and a hook pivoted upon the said drawer attaching member near 60 the rear end thereof and adapted to engage the stop on the lower guide of the intermediate member, said hook being accessible through the opening in the intermediate member when the slide is projected and 65 housed between the intermediate and the draw attaching members when the slide is retracted.

In testimony whereof I affix my signature in presence of two witnesses.

BERT A. LITTLE. [L.S.]
